INVENTOR

UNITED STATES PATENT OFFICE.

ISAAC HIRSOHN, OF NEW YORK, N. Y.

GARBAGE-CAN.

No. 839,588.

Specification of Letters Patent.

Patented Dec. 25, 1906.

Application filed February 8, 1906. Serial No. 300,112.

To all whom it may concern:

Be it known that I, ISAAC HIRSOHN, a citizen of the United States, residing in New York, in the borough of Manhattan, county and State of New York, have invented certain new and useful Improvements in Garbage-Cans, of which the following is a specification.

This invention relates to an improved construction of garbage-cans by which increased strength is imparted to the same, whereby the cans can resist the heavy wear and tear to which they are exposed and in which the cover is locked to the body of the can in an improved manner; and the invention consists of a garbage-can the body of which is formed of a cylindrical shell of suitable sheet metal, top and bottom rims made of pipe provided with a circular slit for the upper and lower ends of the body, and angular braces connecting the upper and lower rims, said braces being riveted to the rims and at their median points of contact.

The invention consists, further, of braces for reinforcing the bottom of the can, and, lastly, of means for holding the cover of the can in locked position on the can-body, as will be hereinafter described and claimed.

In the accompanying drawings, Figure 1 is a side elevation of my improved garbage-can. Fig. 2 is a top view of the same, with a portion broken away. Fig. 3 is a bottom view also with a portion broken away; and Figs. 4 and 5 are detail transverse sections, respectively, on line 4-4, Fig. 2, and on line 5-5, Fig. 1.

Similar letters of reference indicate corresponding parts in the different figures of the drawings.

Referring to the drawings, *a* represents the body of my improved garbage-can. The body is preferably made of stout sheet metal, cylindrical in shape, and provided at the upper and lower ends with reinforcing-rims *b b'*, which are formed of gas-pipe bent into circular shape and soldered together at the abutting ends. The rims *b b'* are provided, respectively, at their lower and upper sides with longitudinal slits into which the upper and lower ends of the body *a* are inserted. It is preferable to use a comparatively light quality of gas-pipe, so as not to unnecessarily encumber the weight of the can. The body *a* is reinforced by means of braces *d*, which are bent at an obtuse angle or made of flat V shape. The upper and lower ends of said

braces are twisted so as to be parallel to the body of the can, while the main portion of each brace projects at an angle of ninety degrees to said body. The twisted upper and lower ends of said braces are connected with the reinforcing-rims *b b'* by means of rivets which pass through the flat ends of the braces and through the rims and body, as shown in Figs. 4 and 5.

The middle short straight portions of the flat V-shaped braces *d* are riveted together, as shown at *r*. As the braces are arranged around the cylindrical body *a* and form a connection between the upper and lower rims *b b'*, they reinforce the body, prevent injury to the same, and hold the rims at the proper distance from each other, so as to prevent any crushing by the strain exerted on the can.

The bottom *a'* is also reinforced against bending in either direction, either by the load placed in the can or from injury from below, by means of angular braces *e*, which are provided with straight middle portions *e'* and ends *e''*, which are bent at right angles to the main portion of the brace, as shown clearly in Fig. 3. The bent-over ends *e''* are riveted to the bottom rim *b'* by means of the same rivets *f* by which the braces *d* of the body are secured to the rims, as shown in Fig. 5, said rivets *f* passing through the bottom rim, the lower end of the body *a*, and the downwardly-bent circumferential flange of the bottom *a'*, as shown in Fig. 5. In this manner these rivets form a very reliable connection between the different parts of the can. The straight middle portions *e'* of the bottom braces *e* abut against each other and are connected by rivets *e''*, so as to resist the inward strain on the bottom rim and reinforce the bottom *a'* against buckling or other injury.

The cover *g* is provided with a handle *g'*, which is provided at its ends with opposite alined elongations or extensions *g''*, one end being bent up, so as to form a lip *g''*, which engages one of two slotted lugs *g'*, that are riveted by the rivets *f* to the upper rim *b* of the can. Said lug *g'* is bent over at its upper end and holds by the bent-up end one handle extension. The opposite end *g''* of the handle extension *g'* is bent up and recessed, said recess registering with the slot in the other lug *g'*, so that the cover *g* can be locked to said last-named lug *g'* by means of an ordinary padlock or be locked by a sliding latch *h*, which is guided on headed pins *h'* on the

cover g , said latch being provided with a bent-up middle portion h^2 , that serves as a handle, and a bent-up end h^3 , reduced in size, which can be pushed through the registering 5 openings in the bent-up end of the handle extension and lug g^4 , so as to lock, in connection with the bent-up end g^5 at the opposite extension of the handle g^1 , the cover of the can. By pushing forward the sliding latch h into 10 the bent-up end h^3 and the lug g^4 the reliable locking connection between can and cover is obtained.

The can is preferably provided with hinged 15 handles of the usual construction.

15. The advantages of my improved garbage-can are, first, the strong and durable construction thereof, so that the same can resist the strain to which the same is subjected in emptying; second, the protection of the 20 sheet-metal body of the can by the reinforcing top and bottom rims and the stiffening braces between the rims; third, the locking connection between the cover and can, so

that the contents of the can are not exposed, and, fourth, the reinforcing of the bottom of 25 the can.

Having thus described my invention, I claim as new and desire to secure by Letters Patent—

A garbage-can comprising a body, tubular 30 top and bottom rims provided with slits for inserting the upper and lower edges of the body, angular braces between the top and bottom rims, means for attaching the upper and lower ends of said braces to the top and 35 bottom rims and upper and lower edges of the can, and means for connecting the middle abutting portions of said braces.

In testimony that I claim the foregoing as my invention I have signed my name in presence of two subscribing witnesses:

ISAAC HIRSOHN.
